UNITED STATES PATENT OFFICE.

HENRY BARDSLEY, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

CAM FOR BAG-LOOMS.

SPECIFICATION forming part of Letters Patent No. 731,655, dated June 23, 1903.

Application filed March 26, 1903. Serial No. 149,695. (No model.)

To all whom it may concern:

Be it known that I, HENRY BARDSLEY, a citizen of the United States, residing at Providence, in the county of Providence and State of Rhode Island, have invented certain new and useful Improvements in Cams for Bag-Looms, of which the following is a specification.

My invention relates to a cam-switch mechanism intended particularly to be used on looms for weaving bags to automatically change the weave to weave the bottom of the bag.

The object of my invention is to provide a cam-switch mechanism of simple construction and automatic operation, and my invention consists in certain novel features of construction of my cam-switch mechanism, as will be hereinafter fully described.

I have only shown in the drawings a cam having my switch mechanism applied thereto and mechanism for automatically operating the switch mechanism, sufficient to enable those skilled in the art to understand the construction and operation thereof.

Referring to the drawings, Figure 1 is a view of one side of a cam having my switch mechanism applied thereto. Fig. 2 is a sectional view showing the opposite side of the cam shown in Fig. 1; and Fig. 3 is a front perspective view of the bearing for the driven shaft, on which the cam shown in Figs. 1 and 2 is secured, and also of the bearing for the rocker-arm, carrying pins to operate the switch on the cam, as will be hereinafter described.

In the accompanying drawings, 1 is a cam having my switch mechanism thereon, to be hereinafter described. The cam 1 has an outer cam-groove 1' in one side thereof and an inner cam-groove 1" leading into the outer groove 1'. The opening or passage into the inner cam-groove 1" from the outer cam-groove 1' is controlled by the switch-pawl 2, to be hereinafter described. (See Fig. 2.) The cam 1 is mounted on and secured to the driving-shaft 3, which is journaled at one end, in this instance in a bearing 4 on a stand 5. Also in this instance on the stand 5 is a bracket 6, having a bearing 6' for one

end of a shaft 7, secured in the bearing 6' by a set-screw 8. On the shaft 7 is loosely mounted to rock thereon the hub 9' of a rock-arm 9 of angle shape at its outer end, with a laterally-projecting pin 10 secured in one angle arm and a second laterally-projecting pin 11 secured in the other angle arm. (See Fig. 3.) To the rock-arm 9 is attached one end of a connector 12. The other end of the connector 12 is attached to mechanism (not shown) for communicating at the proper time a rocking motion to the arm 9, carrying the operating-pins 10 and 11.

On the shaft 7 is fast the hub 13' of the arm 13, which is made yoked or forked at its outer end 13" to receive a lip or projection 9" on the rock-arm 9. The projection 9" on the rock-arm 9 extends between the forked end 13" of the arm 13 and limits the rocking motion of the arm 9, and an adjustable bolt or set-screw 14 through one of the forked arms on the arm 13 provides means for regulating the amount of motion of the rock-arm 9.

On a pin or stud 15 on the face of the cam 1 (see Fig. 1) is loosely mounted a rock-plate 16, having on its opposite edges notches or shoulders 16' and 16", which are in the path of the pins 10 and 11 on the rock-arm 9 when said arm is rocked and the cam 1 is mounted on the driven shaft 3.

A holding-pawl 17 is pivoted at one end on a screw 18 on the cam 1 and has a beveled end adapted to be engaged by the pointed end 16" on the rock-plate 16 and to be moved on the rocking of said plate. After the movement of said plate the pawl extends on one side or the other of the pointed end of said plate to hold it in position. A flat spring 19, secured at one end by a screw 20 to the hub of the cam 1, bears at its free end against the pawl 17 below its pivot-point and acts to hold said pawl against the plate 16.

On the pin 15, on the opposite side of the cam 1 from the plate 16, is loosely mounted one end of the switch-pawl 2, (see Fig. 2,) which is of suitable shape and is adapted to be moved to close the passage from the outer cam-groove 1' to the inner cam-groove 1", as shown by full lines in Fig. 2, or to open the passage, as shown by broken lines, Fig. 2.

The switch-pawl 2 has fast in its upper end above its pivotal support a pin 2', which extends through an elongated opening 21 in the cam 1 and into an open-end slot 16" in the 5 upper end of the rock-plate 16. (See Fig. 1.)

On the cam 1 is a second pin 22, adapted to rock and having fast on one end on one side of the cam 1 a switch-arm 23, (see Fig. 2,) which divides the cam-groove 1" at one end 10 from the cam-groove 1'. The other end of the pin 22 on the other side of the cam 1 has an arm 24, fast thereon, which is engaged by the free end of a spring 25, fast on a block 26 on the cam 1. The spring 25 acts to normally 15 keep the end of the arm 24 in engagement with the projection 27 on the hub of the cam 1, (see Fig. 1.) and the switch-arm 23 closed, as shown in Fig. 2.

The operation of my cam-switch mechanism will be readily understood by those skilled 20 in the art. The revolution of the driven shaft 3 in the direction of arrow *a*, Fig. 3, will cause the cam 1 when fast on said shaft to revolve in the same direction or the direction 25 of arrow *b*, Fig. 1. The revolution of the cam 1 with the switch-pawl 2 in its normal position (shown by full lines, Fig. 2) will communicate through a roll (not shown) extending into the cam-groove 1' a movement to a part 30 to be operated, said movement conforming to the shape of the cam-groove 1'. When it is desired to change the movement, the rock-arm 9 is automatically moved down until the pin 10 thereon extends in the path of and engages the shoulder 16' on the plate 16 in the 35 revolution of the cam 1. The engagement of the pin 10 with the shoulder 16' rocks the plate 16 and disengages it from the pawl 17 and through the pin 2' moves the switch-pawl 40 2 into the position shown by broken lines in Fig. 2, opening the passage into the cam-groove 1" and causing the roll engaging the cam to travel in said groove 1" and open the latch or arm 23 to change the movement of 45 the part operated by the cam 1. The rock-plate 16, held by the pawl 17, remains in this position until the rock-arm 9, carrying the pins 10 and 11, is again moved at the proper time to bring the pin 11 thereon into the path 50 of the rock-plate 16, and the engagement of said pin with the shoulder 16" on said plate rocks the plate and through the pin 2' moves the switch-pawl 2 into the position shown by

full lines in Fig. 2, closing the passage into the cam-groove 1" and causing the roll engaging the cam 1 to travel in the groove 1" to repeat the first movement communicated from the cam 1. The pawl 17 engages the plate 16 and holds it, and with it the switch-pawl 2, in its adjusted position, until again moved by the 60 pin 10, as above described.

It will be understood that the details of construction of my improvements may be varied if desired.

Having thus described my invention, what 65 I claim as new, and desire to secure by Letters Patent, is—

1. The combination with a cam having two different cam-grooves in its surface, of a switch-pawl on the cam for opening and closing the passage between said two cam-grooves, and means for operating said switch-pawl, said means consisting of a rock-plate on the cam connected with said switch-pawl, and a locking or holding pawl for said plate, substantially 75 as shown and described.

2. The combination with a cam having two different cam-grooves in its surface, and a switch-pawl on the cam, for opening and closing the passage between said two cam-grooves, 80 and a rock-plate on the cam connected with said switch-pawl, of means for rocking said plate consisting of a rocking arm carrying two pins, and adapted to be moved to cause one pin to engage and move the rock-plate in one direction, and the other pin to engage and move the rock-plate in the opposite direction, substantially 85 as shown and described.

3. The combination with a cam having two different cam-grooves in its surface, and a switch-pawl on the cam for opening and closing the passage between said two cam-grooves, and a rock-plate on the cam connected with said switch-pawl, and a locking or holding pawl for said plate, of means for rocking said 90 plate, consisting of a rocking arm carrying two pins and adapted to be moved to cause one pin to engage and move the rock-plate in one direction, and the other pin to engage and move the rock-plate in the opposite direction, 95 substantially 100 as shown and described.

HENRY BARDSLEY.
